AIR-COOLED V-TYPE INTERNAL COMBUSTION ENGINE

Charles S. Brown, Syracuse, N. Y.

Original application September 30, 1931, Serial No. 566,073. Divided and this application September 22, 1932, Serial No. 634,415

4 Claims. (Cl. 123—171)

This invention relates to internal combustion engines, and particularly engines in which the cylinders are arranged in banks in V formation or to so-called V types of engine, and has for its object a particularly simple and efficient air cooling system for the V type of engine, whereby currents of air pass lengthwise of the banks between the same and laterally between individual cylinders and other air currents pass lengthwise of the outer side of the banks of the cylinders, whereby the cylinders and the heads are effectively and uniformly cooled, or whereby the uniform distribution of the air around the cylinders is effected.

The invention consists in the novel features and in the combinations and constructions hereinafter set forth and claimed.

In describing this invention, reference is had to the accompanying drawings in which like characters designate corresponding parts in all the views.

Figure 1 is a side elevation, partly in section, of an engine embodying this invention.

Figure 2 is an end elevation partly in section.

Figure 3 is a sectional view, on line 3—3, Figure 1.

Figure 4 is a sectional view, partly diagrammatic, on line 4—4, Figure 3.

This invention comprises generally, a V type of air cooled engine including banks of cylinders arranged in V formation, heads for the cylinders, the heads and cylinders having transverse heat radiating flanges, those being on the cylinders being preferably in a plane at a right angle to the axes of the cylinders and a casing in the form of a box surrounding the cylinders and the heads and provided with air inlets and outlets so arranged as to distribute air currents lengthwise of the banks of cylinders between the same and laterally between the individual cylinders and over the heads and to direct additional air currents lengthwise of the outer sides of the banks of the cylinders, and means, as a fan rotor, mounted on the crank shaft at the front end of the engine having a casing arranged to discharge the air between the banks of cylinders and along the outer sides thereof. Preferably, the casing is formed with inlets and outlets in its front and rear walls and is substantially closed between its front and rear walls, the inlets being arranged in alignment with the space between the banks of cylinders and the spaces between the outer sides of the banks of cylinders and the lateral sides of the casing and the outlets being preferably arranged in line with the banks of cylinders or out of line with the spaces between the banks so that

the air is compelled to take the paths outlined; that is, between the banks of cylinders and laterally between the individual cylinders and over the heads and lengthwise of the outer sides of the cylinders.

1 designates the cylinders which are arranged in V formation, or arranged in two banks A, B, the cylinders being mounted on a common crank case 2 in which the crank shaft 3 is located.

4 designates the heads of the cylinders. These heads are shown as tilted or cocked inwardly toward the interior of the V formation or to stand upright with their axes in substantial vertical line relative to the inclined axes of the cylinders, so that the over-all width of the entire V formation is decreased compared with that of other overhead valve engines where the heads are mounted squarely on the cylinder, or with their axes in line with the inclined axes of the cylinders.

In the engine here illustrated, the valve mechanism is of the overhead type and the head 4 is provided with intake and exhaust passages 5 and 6 which extend respectively toward the inner and outer side of the cylinders, that is, the intake passage extends toward the interior of the V formation and the exhaust passage 6 extends toward the outer side of the V formation. These passages open through the top of the head and communicate respectively with the intake and exhaust manifolds 7 and 8 mounted on the tops of the heads and extending lengthwise of the banks of cylinders. The valves are the usual mushroom or poppet type. The manifolds 7, 8, are located high enough above the cylinders to permit cross currents of air over the cylinder heads and between the cylinders.

10 designates one of the intake valves. The exhaust valve is similar to the intake. The intake and exhaust valves are alike in construction and each has a stem 13 extending upwardly through a valve guide in the head, between the manifolds 7 and 8. The passages 5 and 6 open through ports as 14 into a compression chamber 16 formed in each head. These chambers are deeper on their outer sides, or the sides toward the outer walls of the banks of cylinders, and are here shown as in the form of a truncated cylinder. As the end edges of the cylinders are normal to, or at a right angle to, the axes of the cylinders, the compression chambers 16 are tilted or cocked relatively to the bore of the cylinder. The spark plug 17 extends through the outer or deeper wall of the compression chambers 16.

The location of the spark plug in the longer side of the truncated combustion chamber 16

cates the terminals of the plug as near as possible to the center of the combustion chamber, this lessening the tendency to knock and permitting higher compression than in the usual type of overhead valve chamber where the terminals are not located as near to the center of the combustion space.

The cylinders and heads are provided with heat radiating fins which preferably extend transversely, the fins 18 on the cylinders being inclined, or at a right angle to the axes of the cylinders, and the fins 19 on the cylinder head being horizontal. Owing to the cocked arrangement of the heads, the outer faces of the heads, or the planes 15 of the outer edges of the fins 19 on the head are located on the inner sides of the planes parallel to the axes of the cylinders and tangent to the outer edges of the fins 19 of the cylinders, so that the over-all width of the V formation is 20 greatly reduced compared with the overhead valve V type engines in which the heads are mounted squarely on the cylinders. The location of the intake and exhaust manifolds, on the tops of the cylinders, also contributes to reducing the 25 over-all width of the V formation, and does not interfere with the air passing over the cylinder heads. Preferably, the wall of the intake passages is unprovided with heat radiating fins.

The valve operating mechanism may be of any 30 suitable type. 21 designates rocker arms pivotally mounted at 22 between their ends on a rocker arm support 23, one end of each rocker arm coacting with a valve stem, and the other end of the rocker arm coacting with a lift rod 24, located between the banks of cylinders and coacting with a lifter 25 which in turn coacts with the cam 26 on the cam shaft of the engine. The lifter rod 24 is enclosed in a suitable tube 27. This tube merely serves to enclose the lift rod and does not materially support the rocker arm support 23. There is a rocker arm for each valve stem, and the rocker arms for the valves of each cylinder are arranged on the same support and on axially aligned studs or pivots 22. 40

45 The rocker arm support 23 is provided with a base flange 30 mounted on the top of the head and secured thereto as by bolts 31, and the part of the support which carries the lugs or bearings 32 for the pivots 22 extends laterally inwardly relatively to the V formation over the intake manifold 7 and is spaced apart from the top of the head and the intake manifold.

The overhanging portions of the supports are braced or supported by means connecting each 55 rocker arm support 23 of one bank of cylinders with the other bank of cylinders. This means is here shown as tie-rods 33, each of which is connected at 34 to one rocker arm support 23 and extends across the space between the banks of 60 cylinders and is connected at 35 to the other bank. These tie-rods are arranged in pairs and inclined relatively to each other so that they cross, or are arranged in X formation.

Owing to the manner of supporting the rocker 65 arm supports, the clearances in the valve mechanism between the rocker arms and the valve stems, and the rocker arms and the lift rods, are maintained constant at all temperatures of the engine. It will be understood that the engine 70 cylinders elongate as they become heated, and some compensating means is desirable to maintain a predetermined clearance and efficient valve operation without tappet noise.

Owing to the mounting or bracing 33 of the 75 overhanging portions of the rocker arm supports

23, the shifting of the rocker arm pivots 22 and the rocker arms 21 during cylinder elongation is for the most part horizontal rather than vertical, as in engines where the heads are mounted squarely on the cylinders, and the rocker arms 21 are maintained in proper relation to the valve stems 13 and lifter rods 24 at all engine temperatures and under all conditions. Each of the supports 23 is provided with a suitable removable cap 39 held in position by a nut 40 threading on a stud 41 extending upwardly through the cap from the rocker arm support 23. 42 is a carburetor having branches 43 communicating with both intake manifolds 7.

The subject matter thus far described specifically forms no part of this invention but constitutes the subject matter of my pending application Ser. No. 566,073, filed September 30, 1931, of which this is a division.

This invention relates to a casing or jacket 20 for the banks of cylinders by which the cooling air currents are passed between the banks of cylinders and between the individual cylinders and over the heads thereof and additional air currents passed lengthwise of the cylinders between the outer sides of the banks and the lateral walls of the casing, so that all portions of the individual cylinders and the heads are wiped or washed by the cooling air currents and the air currents distributed uniformly. The casing comprises, generally, side walls 50, a rear wall 51, top wall 52 between the banks of cylinders and below the carburetor rocker arm support and also bottom wall 54 at the lower edges of the side wall 50 so that the casing is in the general form of a box and is formed with inlets and outlets at its front and rear ends so arranged that the air currents pass between the banks of cylinders lengthwise between the individual cylinders laterally and over the heads and lengthwise of the outer sides of the cylinders. The casing between its front and rear walls is preferably unprovided with outlets and the inlets and outlets are arranged out of alignment or so arranged relative to each other that the air currents can not 45 pass straight through the casing but are distributed in the paths before mentioned, preferably, the air currents are created by the rotor of a fan mounted on the front end of the crank shaft 3 in the casing which discharges into a plurality of inlets for the housing.

In the illustrated embodiment of my invention, the casing is provided with three inlets 58, 59, or the fan housing with three outlets arranged respectively in line with the space between the 55 banks of the cylinders and the spaces between the outer sides of the banks and lateral walls 50 of the casing, while the outlets 60 are located in line with the cylinders, or out of line with the spaces between the banks of cylinders. Portions 60 of outlets 60 are also as seen in Figure 4 in line with the spaces between the banks and the lateral walls 50 of the casing.

55 is a fan rotor actuated by the crank shaft 3 and preferably mounted on the front end thereof. 65 56 is a fan housing having outlet branches 57 having openings 58 therein, which communicate with the casing of the engine and provide air inlets for the casing near the opposite side walls 59, or to the outer sides of the banks of cylinders. 70 The fan housing also has outlets 59 which communicate with the spaces between the banks of cylinders beneath the top wall 52 and provide air inlets for the casing.

Preferably, the rear wall 51 has air outlets 60 75

behind the rear cylinders and out of line with 5
passages 59 and extending laterally outwardly to
in line with openings 58 and the spaces between
the side walls 50 and the outer sides of the banks
of cylinders. The object, however, of the back
wall is to direct the outflow of air from between
the bank of cylinders sufficiently around the cyl- 10
inders into the outer paths along the walls 50.
The air which passes through the outlets 59 into
the space between the banks of cylinders is thus
caused to pass between the cylinders and join the
air currents passing to the outer sides of the cyl- 15
inders along the side walls 50. The outlets 60 are
of at least the area of the combined areas of the
fan outlets 58 and 59 and are preferably still
larger to compensate for the expansion of the
air due to heating in its passage around the cyl- 20
inders.

61 is a partition between the outlets 58 and 59
20 to keep the main blast of air from striking the
first cylinders.

To further facilitate the cooling of the cylinders,
the cylinders are arranged in pairs as C and D,
and the space between the cylinders of each pair
25 is less than the space between the pair of cyl-
inders. This arrangement is due primarily to
the fact that a three bearing crank shaft is used.
The relatively cool intake valves are so located as
30 to be adjacent the narrower spaces while the hot
exhaust valves are located adjacent the wider
spaces in order to be swept to a greater extent
by the air currents passing from between the
banks of cylinders to the outer sides of the banks
35 of cylinders, also to permit larger fins surrounding
the exhaust valve passages.

As the intake passages are cooled by the rela-
tively cool incoming of gas or vapor, no cooling
fins are provided for the intake ports or passages,
and hence less space is required for air circulation
40 between the cylinders around the intake valves.
The exhaust valves are located over the engine
center main bearings and at the ends of the pairs
where there is ample room to fin the exhaust
45 valve passages and space for air currents. The
intake ports, which are not ribbed and do not re-
quire as much cooling air, are located in the con-
fined spaces.

What I claim is:

1. In an air-cooled, V-type, internal combus-
50 tion engine, banks of cylinders having heat ra-
diating flanges, a casing surrounding the cyl-
inders in the form of a box having side walls
spaced apart from the outer sides of the banks of
55 cylinders, rear and top walls, the casing having
inlet and outlet openings only at its front and
rear ends respectively, a fan rotor actuated by the
engine and having a casing formed with outlets
60 arranged to discharge air through the inlets of
the engine casing between the banks of cylinders
and along the outer sides of the banks between
the side walls of the casing and the outer sides
65 of the banks, the outlet openings of the casing be-
ing arranged out of line with the inlet openings,
all whereby the air passed between the banks of
cylinders passes around and between the cyl-
inders and joins the air currents passing along
70 the outer sides of the cylinders.

2. In an air-cooled, V-type, internal combus-
70 tion engine, banks of cylinders having heat ra-
diating flanges, heads for the cylinders having heat
radiating flanges, the heads being formed with

intake and exhaust passages and valves for con-
trolling them, intake and exhaust manifolds com-
municating with said passages, a casing sur-
rounding the cylinders and the heads thereof and
being in the form of a box enclosing the banks of
5 cylinders and their heads and having air outlets
in its rear wall and being substantially closed
between its front and rear walls, and a fan in-
cluding a rotor actuated by the engine and hav-
ing a casing formed with an intermediate outlet 10
communicating with the front end of the space
between the banks of cylinders and side outlets
for discharging air around the outer sides of the
banks of cylinders.

3. In an air-cooled, V-type, of internal com-
bustion engine, banks of cylinders having heat
radiating flanges, heads for the cylinders having heat
radiating flanges, the heads being formed
with intake and exhaust passages, and valves for
controlling them, intake and exhaust manifolds 15
communicating with said passages, a casing sur-
rounding the cylinders and the heads thereof,
having side walls spaced apart from the outer
sides of the banks of cylinders, rear and top walls,
the casing having an air outlet opening at its rear
20 end, a fan actuated by the engine and having a
casing formed with an intermediate outlet com-
municating with the front end of the space be-
tween the banks of cylinders and side outlets for
discharging air around the outer sides of the
25 banks of cylinders, the outlet passages for the fan
casing being located substantially in line with the
spaces between the banks of cylinders and with
the spaces between the outer sides of the banks
and the side walls of the casing and the outlet
30 35 passages for the casing around the cylinders, be-
ing located in line with the banks of cylinders and
out of line with said spaces between the banks
and between the outer sides of the banks and the
side walls of the engine casing, all whereby the
40 air passing between the banks of cylinders passes
around and between the cylinders and over the
cylinder heads and joins the air current passing
along the outer sides of the cylinders.

4. In an air-cooled, V-type, of internal combus-
45 tion engine, banks of cylinders having heat ra-
diating flanges, heads for the cylinders having heat
radiating flanges, the heads being formed with
intake and exhaust passages, and valves for con-
trolling them, intake and exhaust manifolds com-
50 municating with said passages, a casing sur-
rounding the cylinders and the heads thereof,
having side walls spaced apart from the outer
sides of the cylinders, rear and top walls, the cas-
55 ing having outlet openings at its rear wall to-
ward the outer side walls and extending in line
with the spaces between the side walls of the cas-
ing and the outer sides of the cylinders of the
banks, a fan actuated by the engine and having
60 a casing at the front of the engine formed with
an intermediate outlet communicating with the
space between the banks of cylinders and side
outlets discharging into the spaces between the
65 side walls of the casing and the outer sides of the
banks of cylinders, all whereby the air passing
through the space between the banks of cylinders
is distributed between and around the cylinders
70 and joins the air currents passing along the outer
sides of the cylinders and out through the outlets
in the rear wall of the casing.

CHARLES S. BROWN.
